Patented Mar. 23, 1915.

UNITED STATES PATENT OFFICE.

JOHN O. CARREY, OF ST. LOUIS, MISSOURI.

LIGHTER.

1,132,559.

Specification of Letters Patent. Patented Mar. 23, 1915.

Application filed November 25, 1914. Serial No. 873,869.

To all whom it may concern:

Be it known that I, JOHN O. CARREY, a citizen of the United States, residing in the city of St. Louis and State of Missouri, have 5 invented a new and useful Lighter, of which the following is a specification.

The present invention relates to lighters adapted for use for lighting cigars and for various other uses to which it may be applied, many of which will be suggested by 10 the following specification and the accompanying drawing.

An object of the invention is to provide a conveniently portable lighter in which there 15 is a spark producing mechanism, a wick communicating with and saturated by an inflammable fluid, and a flame-snuffing hood arranged to move in proximity to the wick to extinguish the flame, in combination with 20 a resilient lever, and a novel form of latch connection between the lever and the hood whereby the lever is retained in engagement with the hood and placed under tension during 25 the initial movement of the handle portion thereof in one direction, with provision for releasing the lever after it has been tensioned, and means whereby the tensioned lever will actuate the spark producing mechanism, and also the hood, so that the wick 30 will be ignited.

A further object is to produce an improved lighter comprising a spark producing mechanism, a wick, and a flame-snuffing hood, in combination with a resilient lever 35 having a handle, a novel form of latching engagement between the lever and the snuffing hood whereby, when the handle is manipulated, the hood will hold the end of the lever until it is placed under tension and will 40 then release the tensioned lever, a connection whereby the lever will actuate the spark producing mechanism when said lever is released as stated, and means whereby the lever will actuate the hood to uncover the 45 wick when the spark producing mechanism is actuated and will actuate the hood to cover the wick when the lever is released.

Having in view the objects above stated, and various other objects which will appear 50 from the following specific description, I have illustrated a preferred embodiment of my invention in the accompanying drawings in which—

Figure 1 is an elevation of the preferred 55 form of the lighter. Fig. 2 is a side eleva-

tion of a portion of the lighter illustrating the improved actuating and controlling lever and its connection with the spark producing mechanism and the flame snuffing hood, the parts being shown in their normal 60 position when the lighter is not in use. Fig. 3 is a similar elevation illustrating the position of the parts after the actuating and controlling lever has been moved to actuate the hood to uncover the wick, and the spark 65 producing mechanism to ignite the wick. Fig. 4 is a plan view of the device. Fig. 5 is a sectional view on the line 5—5 of Fig. 2.

The lighter is preferably of the portable type and, as such, includes a suitable base 1 70 which constitutes a support for maintaining the lighter in a convenient upright position. A receptacle 2 is secured in connection with the base 1, and is arranged to contain the inflammable fluid with which the wick communicates and becomes saturated. The upper end of the receptacle is provided with an opening through which fluid may be poured into the receptacle, said opening being normally closed by a releasable closure 3. An 80 open passage 4 for the wick is secured to the top of the receptacle 2, and contains a wick 5 which extends into the receptacle and into communication with the inflammable fluid therein by which said wick becomes thoroughly saturated so that when the outer extremity thereof is ignited it will maintain a constant flame, as in the case of a lamp wick, for instance.

At one side of the receptacle 2 a bracket 6 90 is secured, and is provided with bearings in which a rock shaft 7 is journaled. The rock shaft 7 extends above the upper bearing and supports a disk 8 having a serrated periphery. The disk 8 is revoluble with respect to the shaft 7 and is retained in position thereon by a releasable nut 9, so that said disk may be removed and replaced with another when it is desirable or necessary so to do. The under side of the disk 8 is provided with 100 an annular series of ratchet teeth 10 adapted to coöperate with a matching toothed surface of a collar 11 which is mounted on the shaft 7 below the disk 8 and which is actuated toward the disk 8 by a coil spring 12 105 encircling the shaft 7 between the lower end of the collar 11 and the upper bearing in which the shaft 7 is journaled. The collar 11 is provided with slots 13 which receive 110 the pins 14 extending from the shaft, and

which prevent the collar from rotating with respect to the shaft 7. Normally the spring 12 holds the teeth of the collar 11 in engagement with the teeth 10, so that when the lever which is hereinafter described is manually operated the collar 11 will rotate the disk 8. At one side of the passage 4 an arm 15 is secured, and in the upper end thereof is mounted a tubular support 16 one end of which opens adjacent to the periphery of the disk 8. A body 17 of suitable spark producing material is supported in a tubular support 16 and is pressed into engagement with the periphery of the disk 8 by a spring 18 mounted in the support 16 between the end of the body 17 and the closed end of a cap 19 which screws onto the threaded exterior of the support 16.

Obviously, by adjustment of the cap 19 the desired tension may be applied to the spring 18 to press the body 17 into engagement with the serrated periphery of the disk 8 with the desired degree of pressure, so that when said disk is forcibly rotated by the collar 11 a spark will be produced by the abrasive action of the disk against the end of the body 17. The arrangement is such that the disk 8 will be rotated in a direction to throw the sparks toward the wick 5 thereby lighting the wick.

At one side of the passage 4 the snuffing hood or flame extinguisher 20 is pivoted upon a support 21. The snuffing hood is in the form of an angular plate having a vertical arm which is pivoted to the side of the passage 4 as stated, and having a laterally extended portion which extends over the wick 5, and a back portion extending at the rear side of the wick. The vertical portion of the hood is provided with an oblique arm 22 having a lateral projection 23 adapted to engage with the front side of the passage 4 to limit backward movement of the hood when the latter is actuated by the resilient action of the controlling lever.

The rock shaft 7 supports two arcuate arms 24 adjacent to the upper one of the two bearings in which said shaft is journaled. The supporting bracket which is secured to the receptacle 2 is provided with two arms 25 which support a small rod 26. A lever 27 is formed with two laterally extending portions 28 by which said lever is pivoted upon the rod 26. The lever may be said to include two parts or members, of which the part 27 constitutes a handle for actuating the coöperating part 29 which is in the form of a resilient plate extending between the pivot rod 26 and the actuating part 27 and having its lower end preferably secured to the hand lever member 27 by a rivet stud 30. Another rod 31 is supported by the arms 25 between the rod 26 and the main body of the bracket and constitutes a support upon which is coiled a part of a spring

32, the lower end of which engages and operates within a notch in the stud 30. The coiled portion of the spring has rigid connection with a part of the bracket so that said spring cannot revolve on the rod 31, 70 thus causing said spring to actuate the handle portion of the lever in a direction away from the receptacle, thus retaining the upper extremity of the resilient member 29 in engagement with the vertical portion of 75 the hood 20. The upper portion of the resilient member 29 extends between the arms 24 and is provided with a curved extremity 33 extending into a notch 34 in the arm 22 of the hood. The notch 34 is in substantially the same horizontal plane as the axis of the pivot 21 on which the hood is pivotally mounted, so that when the handle portion of the lever below the pivot 26 is pressed toward the receptacle the upper end 85 of the resilient member 29 will be held by the engagement of the curved portion 33 within the notch 34, thus causing said resilient member to bend and store up power for the subsequent operation of the rock shaft 90 7 and the hood 20. Continued movement of the handle portion of the lever 27 and the lower portion of the resilient member 29, toward the receptacle, results in drawing the end of the portion 33 out of the notch 95 34 and against the oblique under edge of the arm 22. Since the resilient member 29 was bent and had energy stored therein by the initial movement of the lever 27 toward the receptacle, the said member 29 passes 100 against the oblique under edge of the arm 22 and immediately springs outwardly into contact with the lever 27, thus quickly rocking the shaft 7 and at the same time throwing the hood away from the wick 5 and permitting the spark produced by operation of the disk 8 against the body 17 to ignite the wick and thus produce a flame. Upon release of the lever 27 the spring 32 presses the lower end thereof in a direction away from 105 the receptacle and causes the upper portion of the resilient member 29, which is between the arms 24, to rock the shaft 7 to its initial position, the teeth of the collar 11 escaping over the teeth 10 as will be understood by 110 reference to Fig. 3. Also, the upper end of the resilient member 29 engages against the lower portion of the vertical arm of the hood 20 and restores said hood to its normal position immediately above the wick, thus 115 snuffing out or extinguishing the flame.

As an additional aid for tripping the hood so as to release the upper portion of the resilient member 29 from the notch 34, I prefer that the upper end of the lever 27 be of such length that the outward movement thereof will cause said lever to engage the lower extremity of the arm 22, and thus trip or assist in tripping the hood to permit the resilient member 29 to throw the hood back 120 125 130

and to actuate the spark producing mechanism. This action will only occur when the member 29 fails to throw the hood back by the movement of the resilient member out of the notch 34.

It will be understood that there may be variations in the arrangement of the parts whereby the resilient member will actuate the hood and the spark producing mechanism, without departure from the principles of the invention. Therefore I do not restrict myself to the precise details illustrated and described but

What I claim and desire to secure by Letters Patent is:

1. A lighter, comprising a rock shaft, a spark producing mechanism controlled by said rock shaft, a wick, a flame extinguishing hood movable adjacent to said wick, a resilient member having one end in releasable latched engagement with said hood and becoming released from said latched engagement by the bending movement of said resilient member, a lever for bending said member and releasing said latched engagement between said member and said hood, means whereby said resilient member will rock said shaft to actuate said spark producing mechanism when said latched engagement is released, and means for restoring said resilient member into latched engagement with said hood.

2. A lighter comprising a wick, a flame extinguishing hood movable to and from said wick, a resilient member, a support on which said resilient member is mounted, a releasable connection between said member and said hood whereby said member is retained in latched engagement with said hood when the opposite end of said member is moved, a lever operable to bend said member during the initial movement thereof and to release said connection between said member and said hood during the final movement thereof in one direction, a spark producing mechanism adjacent to said wick, and means for actuating said spark producing mechanism by the movement of said resilient member after release of said releasable connection with said hood.

3. In a lighter, the combination with a shaft, a spark producing mechanism controlled by said shaft, a wick supported in position to be ignited by said spark producing mechanism, a flame extinguishing hood movable to and from said wick, a support, a handle pivotally carried by said support, a resilient plate between said support and said handle, a connection between the lower end of said plate and said handle, a connection between the upper end of said plate and said hood effective to hold the upper end of said plate during the initial movement of said handle and to release said plate during the final movement of said handle, means where-

by said plate will actuate said hood away from said wick when said plate is released as aforesaid, and means whereby said plate will actuate said spark producing mechanism, substantially as described.

70

4. In a lighter, a wick, a pivotally supported plate, a spark producing mechanism, a shaft for actuating said spark producing mechanism, a resilient element having releasable latch connection with said plate, a handle for operating said resilient element to release said latch connection, means whereby said resilient element will operate said shaft, and means for restoring said element into latched engagement with said plate, substantially as described.

75

5. In a lighter, the combination with a wick, a spark producing mechanism operable to ignite said wick, and a flame extinguishing hood movable to and from said wick, of a rod supported below said mechanism and said hood, a resilient lever bearing against said rod and releasably engaging said hood, an element engaging said rod and operable to actuate the lower end of said lever effectively to bend said lever and to tension said lever during the initial movement of said element and to release said lever from said hood during the final movement of said element, means holding said element in engagement with the lower end of said lever, a projection on said hood extending into the path of movement of said lever whereby said lever will actuate said hood away from said wick when said lever is released as aforesaid, means whereby said lever will actuate said spark producing mechanism, and a spring actuating said lever to restore said hood to its normal position adjacent to said wick.

90

6. In a lighter, a wick, a flame extinguishing hood pivotally mounted adjacent to said wick and having a notch in one edge thereof, a projection extending below said notch, a resilient lever engaged in said notch, a handle member for actuating one end of said lever while the other end of said lever remains seated in said notch whereby said lever is placed under tension by the movement of said handle, said lever being drawn out of said notch by the final movement of said handle and operating against said projection effectively to spring said hood away from said wick, and a spark producing mechanism operated by said lever, substantially as described.

105

7. In a lighter, a shaft, a spark producing mechanism controlled by said shaft, arms extending from said shaft, a pivoted element, a fulcrum member, a resilient plate bearing against said fulcrum member and engaging said arms and being in releasable latched engagement with said pivoted element and becoming released from said latched engagement by the bending movement of said

110

115

120

125

130

plate, a lever for bending said plate and releasing said latched engagement between said plate and said element, means holding said plate and said lever in proper relative position, and means for restoring said plate into latched engagement with said element.

In witness whereof, I have signed this

specification in the presence of two subscribing witnesses.

JOHN O. CARREY.
